UNITED STATES PATENT OFFICE.

LAWRENCE ROY MOORE, OF SAN RAFAEL, CALIFORNIA.

ATTACHMENT FOR OVERSHOES.

1,189,989.

Specification of Letters Patent.

Patented July 4, 1916.

Application filed April 28, 1915. Serial No. 24,487.

To all whom it may concern:

Be it known that I, LAWRENCE ROY MOORE, a citizen of the United States, and a resident of San Rafael, in the county of Marin and State of California, have invented a new and Improved Attachment for Overshoes, of which the following is a full, clear, and exact description.

My invention relates to an attachment for an overshoе for use in pulling the overshoе onto a boot or shoe.

Objects of the invention are to provide an overshoе with a non-elastic pull-on loop so formed and located as to prevent the hands of the wearer from being soiled in pulling on the overshoе; to provide an overshoе with a pull-on loop so located and secured as to lie beneath the ordinary boot or shoe between the same and the overshoе, when the latter is in use, whereby the loop will be out of view; and to provide a pull-on loop that will be very effective in facilitating the pulling on of the overshoе.

The invention will be particularly explained in the specific description following.

Reference is had to the accompanying drawings forming part of this specification, in which similar characters of reference indicate corresponding parts in all the views, and in which:

Figure 1 is a sectional plan view of an overshoе having my improved pull-on loop applied, parts of the overshoе being broken away; Fig. 2 is a side elevation partly in vertical section; Fig. 3 is a detail transverse vertical section on the line 3—3 Fig. 1; Fig. 4 is a sectional plan view showing a modified construction; and Fig. 5 is a perspective view of the strip from which the improved pull-on loop is formed.

In carrying out my invention in practice, a non-elastic pull-on loop generally designated by the numeral 10 is disposed on the sole of the overshoе A forward of and adjacent to the shank B. The loop is made from a strip of tape as indicated in Fig. 5, the strip being bent into U-form as shown in Figs. 1 and 4, presenting forwardly extending members 11. The members 11 are entered through transverse slits 12 in the inner sole α of the overshoе, and lie in depressions in the upper side of the sole A to be flush with the upper surface of the latter, as clearly shown in the cross-section Fig. 3. The ends 11 may be secured by any

suitable adhesive material, or otherwise. It will thus be seen that the bend of the loop lies at the shank B, the general direction of the loop and its arms 11 being lengthwise of the sole and the bend being disposed in the direction of the heel of the overshoе.

To pull the overshoе on to a boot or shoe the heel portion of the overshoе will be depressed and the toe of the boot or shoe entered into the overshoе. The loop 10 may be conveniently grasped without the hands of the wearer being soiled, and an effective pull may be exerted rearwardly until the heel portion of the overshoе is in position to be drawn upward into place. With the overshoе in position, the loop 10 will be beneath the boot or shoe, the bend of the loop being pressed down at the shank.

In the form shown in Fig. 4 the loop 10 is applied the same as previously described, the forwardly extending ends thereof being entered through the slits 12 in the inner sole of the overshoе. In this form, however, I have shown a reinforce 13 which is slotted as at 12^a coincidentally with the slits 12 in the inner sole, and the ends 11 are passed through the said reinforce. Suitable adhesive material may be employed to hold the reinforce 13 in position.

The foregoing construction affords a practical means for carrying my invention into effect, and I would state in conclusion that I do not limit myself strictly to the exact details herein illustrated, since, manifestly, the same can be considerably varied without departing from the spirit of the invention, as defined in the appended claims.

Having thus described my invention, what I claim as new and desire to secure by Letters Patent, is:

1. The combination with an overshoе, of a pull-on device therefor, comprising a non-elastic member having one portion secured to the overshoе bottom forward of its shank and another portion extending backwardly therefrom inside the overshoе a distance sufficient to enable it to be grasped for pulling-on the overshoе and constructed and arranged to lie wholly within the overshoе while the latter is in use.

2. The combination with an overshoе, of an inelastic, non-extensible member secured longitudinally along the overshoе bottom, and having a rearwardly extending portion free from the sole and forming a handheld

and pulling grip, and a transverse reinforce for said member contiguous to the junction of the fixed and loose portions thereof.

3. An overshoe having on the bottom 5 thereof at the interior, a pulling-on attachment presenting a loop having side members forwardly disposed and united to the material forming the outer sole of the overshoe, the said forwardly extending ends of 10 the loop lying beneath the inner sole of the

overshoe and a transverse reinforce strip beneath the inner sole through which strip said ends of the loop extend.

In testimony whereof I have signed my name to this specification in the presence of 15 two subscribing witnesses.

LAWRENCE ROY MOORE.
